UNITED STATES PATENT OFFICE.

ERICK P. BERGMAN AND ARTHUR E. RENARD, OF CONCORDIA, KANSAS.

EXTENSIBLE BEDSTEAD.

SPECIFICATION forming part of Letters Patent No. 674,725, dated May 21, 1901.

Application filed February 27, 1901. Serial No. 49,043. (No model.)

To all whom it may concern:

Be it known that we, ERICK P. BERGMAN and ARTHUR E. RENARD, citizens of the United States, residing at Concordia, in the county 5 of Cloud and State of Kansas, have invented new and useful Improvements in Extensible Bedsteads, of which the following is a specification.

This invention relates to certain new and 10 useful improvements in bedsteads; and it consists in the particular construction and arrangement of the parts which provide means whereby the bedstead can be extended laterally to provide for either a single or double 15 bed, as will be hereinafter set forth.

In the accompanying drawings, Figure 1 is 20 a perspective view of a bedstead constructed in accordance with our invention, in which view the side bars are shown extended. Fig. 20 2 is a detail view of one end of the bed, partly in section; and Fig. 3 is a detail perspective view of one of the slats.

A bed made up in accord with our invention is preferably constructed entirely of metal, 25 the posts A being tubular and provided at a suitable distance above their lower ends with apertures which are adapted to receive hooks b, which project from the end pieces of the sides B. The lower bars of the sides B are 30 preferably made angular, said angle-bars B' having through the horizontal flange openings b', which are adapted to receive pins c, which depend from the ends of each section of the slats. The slats are each made up of two 35 parts C C', the part C being bifurcated to provide parallel side members, between which the reduced portion of the part C is secured by means of plates d d', which are rigidly attached to the ends of the members of the slats. 40 By the construction shown we provide slats which are longitudinally extensible and can be moved with the side pieces of the bed.

The posts A, at right angles to the side pieces B B, have rigidly attached thereto inwardly-projecting tubes D D', each having therethrough longitudinal slots e and below the slots a plurality of perforations e'. The 45 posts above the lower tubes D carry inwardly-projecting sections H H, which are ornamented 50 to correspond with the ornamentation of the side pieces, above the angle-bar thereof.

F refers to the central sections of the head

and foot board, and on a line with the tubes D D' are larger tubes E E', into which the tubes D D' may slide. The tubes E have in 55 their lower portion longitudinal slots, and in said slots are placed latches G, the same being secured to the tubes by transverse pins g. The latches are constructed to provide near the pins depending portions, above which 60 are springs g', which tend to force the inwardly-projecting ends g'' of the latches in engagement with the apertures e'. It will be noted that the outwardly-projecting ends of the latches carried by each bar are near each 65 other, so that they may be readily manipulated by one hand while the other hand actuates the latches on the corresponding bar above; also, that the springs are entirely 70 enclosed and the latches are hidden, as they lie mostly within the tubes and the slots therein. When the latches are operated to remove their catch ends from the holes e', the side sections and the posts, together with the extensible slats, can be adjusted to make the 75 bed wider or narrower, as desired.

The inwardly-projecting sections H H, which are carried by the posts, may lie snugly against a correspondingly-ornamented end piece attached to the center tubes E. 80

We are aware that prior to our invention bedsteads have been made with hollow head and foot boards to receive pieces which project from the posts and enter the recess to provide means for extending the width of the 85 bed, and we do not claim such construction, broadly; but

What we claim as new, and desire to secure by Letters Patent, is—

1. In a metal bed having side pieces, the combination of corner-posts having inwardly-projecting tubes D D' said tubes having longitudinal slots and perforations below said slots, inwardly-projecting sections carried by the corner-posts on a line with the side pieces 95 of the bed, central sections having upper and lower slotted tubes, spring-actuated latches attached to the slotted central sections to engage with the apertures in the tubes attached to the corner-posts, and pins attached to the 100 tubes to engage the longitudinal slots in the tubes attached to the post, substantially as shown and for the purpose set forth.

2. In combination with the posts and side

pieces of a bedstead, the posts having inwardly-projecting sections on a line with the side pieces and at right angles thereto, tubes which project from the posts said tubes having therethrough longitudinal slots and below the slots a plurality of apertures, central head and foot sections each section including upper and lower tubes which are connected to each other, the tubes having near their ends pins which engage the slots through the tubes carried by the posts, and spring-actuated catches attached to the upper and lower tubes

of the central sections and engaging said apertures, the parts being organized substantially as shown.

In testimony whereof we have hereunto set our hands in presence of two subscribing witnesses.

ERICK P. BERGMAN.
ARTHUR E. RENARD.
